Primary Examiner — Lauren R Calve*(74) Attorney, Agent, or Firm* — Lee & Hayes, P.C.(57) **CLAIM**

The ornamental design for a grip aid, as shown and described.

DESCRIPTION

FIG. 1 is a bottom, back perspective view of a grip aid;

FIG. 2 is a top, front perspective view thereof;

FIG. 3 is a front view thereof;

FIG. 4 is a back view thereof;

FIG. 5 is a top view thereof;

FIG. 6 is a bottom view thereof;

FIG. 7 is a left-side view thereof; and,

FIG. 8 is a right-side view thereof.

The dot-dashed broken separation lines disclaim the length of the grip aid. The separation lines and portion between the separation lines form no part of the claimed design.

The dashed broken lines depict portions of the grip aid that form no part of the claimed design.
